DESIGN FOR A BUTTON OR SIMILAR ARTICLE

Morton Berkman, Forest Hills, N. Y.

Application March 15 1939, Serial No. 83,584

Term of patent 3½ years

To all whom it may concern:

Be it known that I, Morton Berkman, a citizen of the United States of America, residing in Forest Hills, city of New York, Borough of Queens, county of Queens, and State of New York, have invented a new, original, and ornamental Design for a Button or Similar Article, of which the following is a specification, reference being had to the accompanying drawing, forming part thereof, wherein,

Figure 1 is a front view of a button or similar article showing my new design.

Figure 2 is a rear view thereof.

Figure 3 is a top edge view of the shank portion of the button or similar article shown in Figure 2.

I claim:

The ornamental design for a button or similar article, substantially as shown.

MORTON BERKMAN.
